UNITED STATES PATENT OFFICE.

CHARLES E. STACY, OF DAYTON, OHIO.

AIRPLANE.

1,311,097.

Specification of Letters Patent. Patented July 22, 1919.

Application filed May 27, 1918. Serial No. 236,744.

To all whom it may concern:

Be it known that I, CHARLES E. STACY, a citizen of the United States, residing at Dayton, in the county of Montgomery and State of Ohio, have invented certain new and useful Improvements in Airplanes, of which the following is a specification.

This invention relates to improvements in airplanes of the biplane type. The object 10 of the invention is to provide an airplane having the property of self-balancing or inherent stability. This is accomplished by means of control planes constructed and arranged relatively to the main sustaining 15 planes so as to achieve the above object. The controlling system is what may be termed a diagonal axis control. Other objects are attained, due to the use of the control planes, briefly stated, such as the concentration of 20 weight to the center of the machine; the possibility of constructing very light plane extremities which enable the machine to be alert; and a control system free from connecting wires and pulleys whereby lost motion 25 between the control stick and the movement of the control planes is avoided.

Preceding a particular description of my invention reference in general terms is first made to the accompanying drawings of 30 which Figure 1 is a plan view of an airplane embodying my improvements. Fig. 2 is a front elevation of the same. Fig. 3 is a side elevation of the same. Fig. 4 is a fragmentary plan view of the controlling devices, parts of the control planes and spars being broken away and the outline of portions of the planes appearing in broken lines. Fig. 5 is an elevation of the controlling devices, parts appearing in section and parts 40 of the control plane spars broken off.

In a particular description of the invention similar reference letters indicate the same parts in the several views of the drawings.

Referring to the two main views, A—A 45 designate the two main sustaining planes constructed of material best adapted to the requirements, the same being supported and connected by means of struts α and cross brace wires b and attached to a fuselage or central body B, said fuselage supporting the engine and propeller in the usual way. The 50 control wings or planes C—C which constitute the invention may be of any suitable 55 shape to serve their purpose. In the drawings they are shown of oblong form, some- what resembling a canoe paddle in that they gradually increase in width as their length progresses. In the drawings two of these 60 controlling planes are shown. The number of these controlling planes may, however, be increased in the case of very large ships. The said controlling planes are made of light 65 frame work covered with fabric and treated with what is called "dope" in common 70 shop parlance, otherwise known as a particular varnish which imparts a water-proof and air-tight character to the plane surfaces. The said controlling planes each have a spar D extending the length thereof and 75 forming the longitudinal axis thereof. The 80 positions of the controlling planes relative to the main planes are substantially as shown in Fig. 1, their inner ends extending approximately to the center of the machine. 75 The inner ends of the controlling plane spars D are mounted in thrust ball-bearings E in a manner that allows said controlling planes to turn freely the axes D running through 85 their lengths, said controlling planes extending 80 outwardly from the center of the machine and drifting rearwardly on diagonal lines with the lateral axis of the machine. The 90 back sweep of the controlling planes may be varied more or less according to the special design of the airplane in general, and they may be slightly elevated or lowered as they sweep backwardly as compared to the line of propeller thrust. As before 95 stated they are supported by means of thrust ball-bearings which are in turn fastened to the top of the fuselage or other centrally located frame work of the machine, and by means of tie or brace wires c connected to the 100 controlling plane spars at several points and running to suitable points d on the machine 105 in a manner to hold said controlling planes rigid and at the same time allow them to turn something over a quarter revolution, on their axes. The inner ends of the controlling 110 plane spars D extend through the thrust ball-bearings E and have attached to them by means of clamps, lever-arms F which extend downward in such manner that when the controlling planes are rocked on their axes the said lever-arms will move to and fro. The said lever-arms F are fastened firmly to the controlling plane spars D and to the lower ends of said lever-arms are connected arms G which are provided with ball and socket joints H or other suitable antifriction joints which connect the lower

ends of the lever-arms F to the control stick I about one-third the length of the control stick from the floor J of the fuselage. The control stick I is connected to the floor by a ball and socket joint K which allows it to have a universal movement in all directions. A movement of the control stick backward will similarly move the control planes, and a movement of said control stick sidewise 10 will cause a reversal of the control planes. If the control stick is moved forward or backward as above indicated, the control planes act in the capacity of an elevator, and if moved sidewise they act in the capacity of a combination of rudder and ailerons. The control planes provide the craft with an inherent self-righting capacity 15 thereby allowing concentration of weight

and rendering it possible to build comparatively light wing tips as hereinbefore stated. 20

Having described my invention I claim:

In an airplane, control planes separate from the main planes and attached to the airplane centrally and extending diagonally rearwardly, and at other points by 25 means of wires, said control planes extending outwardly and drifting rearwardly on a level with the thrust line of the propeller, and being capable of turning on axes extending through their lengths, and means 30 for manually controlling the turning of the control planes from a pilot seat, said means including levers interposed between the control stick and the control planes.

In testimony whereof I affix my signature. 35

CHARLES E. STACY.
